A. MILLER

CONTAINER

Filed June 28, 1922

FIG. 1.

FIG. 2.

Inventor:
Arthur Miller,
By Dyrnforth, See, Clinton, Wicks,
Attys.

UNITED STATES PATENT OFFICE.

ARTHUR MILLER, OF OAK PARK, ILLINOIS.

CONTAINER.

Application filed June 28, 1922. Serial No. 571,426.

To all whom it may concern:

Be it known that I, ARTHUR MILLER, a citizen of the United States, residing at Oak Park, in the county of Cook and State of Illinois, have invented a new and useful Improvement in Containers, of which the following is a specification.

My invention relates, more particularly, to milk cans, my objects being to provide a novel, simple and economical construction of can which may be readily cleansed thereby rendering it highly sanitary, and which shall be very durable of construction, adapting it to withstand to a high degree the stresses to which cans are subjected in the rough handling of the same; to reduce the amount of material required in the constructing of a can; and generally to so improve upon containers, particularly milk cans, as hitherto constructed, as to render them better adapted to the use for which they are provided.

Referring to the accompanying drawing: Figure 1 is a view in vertical sectional elevation of a milk can constructed in accordance with my invention; and Figure 2, an enlarged broken section taken at the line 2—2 on Fig. 1 and viewed in the direction of the arrows.

In accordance with the preferred, illustrated embodiment of my invention I form the can of an upwardly-dished bottom section 3, the upper marginal annular edge-portion of which, represented at 4, forms the lower portion of the side wall of the can; an annular butt-strip 5 encircling the bottom portion 3 and extending at its lower edge below the bottom surface of the portion 3 and forming a rest for the can, a cylindrical side-wall-forming section 6 surmounting the portion 4 of the section 3 and surrounded by the upper edge-portion of the butt-strip 5; a downwardly-flaring breast-portion 7 of frustro conical shape in cross-section surmounting the upper edge of the wall-forming section 6, the latter and the lower edge of the breast 7 being surrounded by a band 8; and an integral neck-and-lip portion 9 surmounting the upper, smaller end of the breast 7.

The sections 6 and 7 are each shown as formed of a single sheet of metal bent into circular shape, the metal forming the section 6 to form a cylinder and the metal forming the breast 7 to form the hollow frustro-conical section 7, with the respective

edges of the metal sheets joined together in any desirable way to form liquid-tight joints represented at 10 and 11. These joints by preference are formed in accordance with the method set forth in my application for United States patent executed concurrently herewith and involving the step-welding of the edges of the sheet arranged in overlapped relation to form a continuous weld at the joints, and the subjection of the metal at the joint to a rolling action to harden the metal softened in the welding operation and smoothing it to render the joint readily cleansed, Figure 2 showing the finished joint by a view in cross-section.

The neck-and-lip portion 9 is preferably constructed by drawing it from metal of any suitable gage and swedging its lower open portion to form a downwardly and outwardly-flaring continuous flange 12 at which the section 9 overlaps the upper extremity of the section 7 and to which it may be secured in any desirable way, as for example by step-welding it thereto to form a continuous annular fluid-tight joint.

The bottom-forming member 3 is preferably formed of Bessemer metal shaped to present the form shown and form a relatively heavy bottom for the can. The side-wall-forming portion 6 is not required to be of as heavy gage metal as the bottom section 3, but as it is desired that the inner surface of the section 6 be vertically flush with the inner surface of the portion 4 of the section 3, I form the butt-strap 5 as shown, this feature of my invention being presented in an application for United States patent executed concurrently herewith. In accordance with the showing in the drawing, I provide about the inner surface of the butt-strap 5, at the portion thereof which opposes the portion 4 of the bottom 3, an annular recess 13 into which the portion 4 extends, this recess being of such depth that when the sections 3 and 6 are assembled, as shown, the inner surface of the section 6 and the inner surface of the portion 4 will be flush in a vertical plane. With the parts just referred to assembled as stated, they are welded together, preferably by step-welding them to form them into a unitary structure presenting a liquid-tight joint between these parts, it being preferred that the joint thus produced be tinned.

Referring now to the joining of the sections 6 and 7, the band 8 is shown as pro-

vided with an upwardly and inwardly inclined annular flange 14 which overlaps the lower end of the section 7 at the outer surface of the latter. The band 8 is secured, 5 in any desirable manner, at its flange 14 to the breast 7, as for example by welding it thereto, and at its lower portion to the upper edge portion of the section 6 in any desirable manner as by soldering it to the 10 latter.

It will be manifest from the foregoing that by constructing a can in accordance with my invention many advantages are obtainable, among which are, those portions 15 of the can which are not required to be constructed of relatively heavy material may be more lightly constructed, which involves great savings not only in the cost of manufacture of the cans but also in transportation charges, and permits of the can being made of lighter weight than possible in the case of prior constructions. Thus, as shown in the drawing, the neck-and-lip section 9, and the bottom section 3, are constructed of 20 heavier metal than the side sections 6 and 7, as the first-referred-to sections are subject to greater stresses in use than the wall sections 6 and 7. Another advantage of the construction is that I am enabled to construct the bottom-forming member of the 25 can of Bessemer metal, whereas in milk cans as now commonly used it is necessary that the bottom sections be constructed of open hearth metal. Furthermore, danger 30 of leakage of the contents of the can from the joint adjacent the bottom of the can is reduced to the minimum, as the joint formed as shown and above described is very effective and durable.

Referring more particularly to the feature of forming the breast and neck portions separately, this is of great advantage especially in milk cans. It often happens that cans are stacked and unless the metal 40 of the necks is sufficiently heavy to withstand expansion by the jamming of the covers into the necks, the covers become loose in the necks and milk is spilled in transit. By my invention the neck portion may be 45 made of sufficiently thick metal to withstand the stresses to which it is subjected in use, including those to which it is subjected when the covers are jammed into the necks as stated, without rendering the cans 50 unduly heavy, as the breast portion may be made of lighter metal sufficient to resist the stresses to which it is subjected.

While I have illustrated and described a particular construction embodying my invention, I do not wish to be understood as intending to limit it thereto as the same may be variously modified and altered without departing from the spirit of my invention.

What I claim as new, and desire to secure 65 by Letters Patent, is:

1. A container comprising a lower section presenting a bottom proper from which rises at the marginal edges of the latter, a continuous flange portion, a side-wall-forming section superposing said lower section, 70 and a band member surrounding the joint between said sections and flatwise opposed by the latter and to which both of said sections are united as by welding.

2. A container comprising a lower section 75 presenting a bottom proper from which rises at the marginal edges of the latter a continuous flange portion, a side-wall-forming section superposing said lower section, 80 and a band member surrounding the joint between said sections and flatwise opposed by the latter, said sections being united together, as by welding, and each united to said band member.

3. A container comprising a lower section 85 presenting a bottom proper from which rises at the marginal edges of the latter, a continuous flange portion, a side-wall-forming section of thinner metal than said flange 90 of said lower section, and a band member surrounding the joint between said sections and flatwise opposed by the latter, the inner surface of said band member being recessed to receive the upper edge portion of said flange, said band being united to both of 95 said sections as by welding.

4. A container comprising a lower section presenting a bottom proper from which rises at the marginal edges of the latter a continuous flange portion, a side-wall-forming section of thinner metal than said flange 100 of said lower section, and a band member surrounding the joint between said sections and flatwise opposed by the latter, the inner surface of said band member being recessed to receive the upper edge portion of 105 said flange, said sections being united together, as by welding, and also each united with said band.

5. A container comprising a lower section 110 presenting a bottom proper from which rises at the marginal edges of the latter a continuous flange portion the outer surface of which is a plain surface, a side-wall-forming section of thinner metal than said flange 115 of said lower section, and a band member surrounding the joint between said sections and flatwise opposed by the latter, the inner surface of said band member being recessed to receive the upper edge portion of 120 said flange, said band being united to both of said sections as by welding.

6. A container comprising a lower section presenting a bottom proper from which rises at the marginal edges of the latter, a continuous flange portion, a side-wall-forming section of thinner metal than said flange 125 of said lower section, and a band member surrounding the joint between said sections and flatwise opposed by the latter, the in- 130

- ner surface of said band member being recessed to receive the upper edge portion of said flange and inset inwardly beyond the outer surface of said flange, said band being united to both of said sections, as by welding.
7. A container comprising a lower section presenting a bottom proper from which rises at the marginal edges of the latter, a continuous flange portion, a side-wall-forming section of thinner metal than said flange of said lower section and in its entirety extending above said lower section, and a band member surrounding the joint between said sections and flatwise opposed by the latter, the inner surface of said band member being recessed to receive the upper edge portion of said flange, said band being united to both of said sections as by welding.
8. A container comprising a side-wall-forming section, a breast section, and a band surrounding the joint between said sections and provided with an upwardly and inwardly-flaring flange at which said band overlaps the lower edge of said breast, said band being located wholly at the outer surfaces of said breast and section and connected with said section and with said breast.
9. A container comprising a side-wall-forming section, a breast section, and a band surrounding the joint between said sections and provided with an upwardly and inwardly-flaring flange at which said band overlaps the lower edge of said breast, said band being welded to said breast and soldered to said section.
10. A container comprising a breast portion and a neck portion surmounting said breast portion, said breast portion and said neck portion being formed separately and united together, said neck portion being of thicker metal than said breast portion.
11. A container comprising a breast portion and a neck portion surmounting said breast portion, said breast portion and said neck portion being formed separately, said neck portion being formed with a downwardly and outwardly-inclined flange portion at which it overlaps the upper edge portion of said breast and at which these parts are united, the metal of said neck portion being thicker than said breast.
12. A container comprising a breast portion and a neck and lip portion surmounting said breast portion, said breast portion and said neck and lip portion being formed separately, said neck and lip portion being formed with a downwardly and outwardly-inclined flange portion at which it overlaps the upper edge portion of said breast and at which these parts are united, the metal of said neck and lip portion being thicker than said breast.

ARTHUR MILLER.
